[57] CLAIM

The ornamental design for a dentist service unit, as shown and described.

DESCRIPTION

FIG. 1 is a front perspective view of a dentist service unit showing my new design;

FIG. 2 is a front elevational view thereof; and

FIG. 3 is a top plan view thereof.

The rear of the unit is substantially flat and unornamented.

FIG. 1.

FIG. 2.

FIG. 3.
